(57) **CLAIM**

I claim the ornamental design for the vending machine, as shown and described.

DESCRIPTION

FIG. 1 is a perspective view of the vending machine of the present invention.

FIG. 2 is a front view of the vending machine of the present invention.

FIG. 3 is a side view of the vending machine of the present invention.

FIG. 4 is a back view of the vending machine of the present invention.

FIG. 5 is a side view of the vending machine of the present invention.

FIG. 6 is a top view of the vending machine of the present invention; and,

FIG. 7 is a bottom view of the vending machine of the present invention.

The portions of the vending machine shown in broken lines form no part of the claimed design.
